US0D1082967S

(12) **United States Design Patent** (10) **Patent No.:** **US D1,082,967 S**
(45) **Date of Patent:** **** Jul. 8, 2025**

(54) **DOLL**

(71) Applicant: **Shenzhen Beisheng Technology Co., Ltd.**, Shenzhen (CN)

(72) Inventor: **Weilin Li**, Harbin (CN)

(73) Assignee: **Shenzhen Beisheng Technology Co., Ltd.**, Shenzhen (CN)

(**) Term: **15 Years**

(21) Appl. No.: **29/978,831**

(22) Filed: **Dec. 16, 2024**

(30) **Foreign Application Priority Data**

Jun. 22, 2024 (CN) 202430385430.4

(51) **LOC (15) Cl.** **21-01**

(52) **U.S. Cl.**

USPC **D21/627**
